UNITED STATES PATENT OFFICE.

DRAGUTIN ZABARATZ, OF BELGRADE, SERBIA.

DROPPING SCENE.

1,404,919.

Specification of Letters Patent. Patented Jan. 31, 1922.

Application filed March 25, 1920. Serial No. 368,702.

To all whom it may concern:

Be it known that I, DRAGUTIN ZABARATZ, a subject of the Kingdom of Serbia, residing at Belgrade, in the Kingdom of Serbia, have 5 invented certain new and useful Improvements in Dropping Scenes; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 In theatrical practice various systems of scenes have been employed, which may be classed in three particular groups, viz., revolving scenes, shifting scenes and dropping scenes, all of which have the object of facilitating the changing of the scenery seen on 20 the stage.

All of these systems, however have certain disadvantages, so that they have not found a very extended adoption. Revolving scenes 25 will for reason of the space required by them, prevent the whole area of the stage being utilized, so that, when such revolving scenes are used, many pieces cannot be played at all, because these revolving scenes render 30 only a small depth of scene available. Shifting scenes are such, with which on either side of the stage proper, and in the level of the same, large chambers are provided, communicating with the stage 35 through wide doors; in these chambers the new scenes and properties are built up, ready to be shifted on to the stage, whilst the scene last shown is shifted into the opposite chamber. Obviously this arrangement necessi- 40 tates a large space in the level of the stage, and it is not always possible or at least difficult to obtain such space, and will with already existing theatre buildings even sometimes be impossible, or considerably increase 45 the costs for new theatre buildings. With dropping scenes the floor of the stage is divided into three sections of practically the same size. Of these the foremost, or the two foremost, and but rarely all three are used 50 for the scene. When the foremost section is being used as a scene, the next scenes and properties may be built up on the middle and the rearmost section. In many instances, however, and in particular, when 55 the two foremost, or so much the more, when all three sections have to be used for one

scene, this arrangement does not afford any advantage whatever. Furthermore this system, the same as also the hereinbefore mentioned two other systems only allow of preparing the following or, at the utmost, the two following scenes. 60

With the present invention a stage of modern construction, without wings, loft ceiling or the like is employed. The whole 65 floor of the stage is empty whilst a spherical horizon—for use with deep sceneries—is vaulted over the whole stage room, and an open circular horizon encircles the stage at a suitable depth. 70

The scene arrangement according to the present invention is shown in the accompanying drawing in an embodiment by way of example.

Fig. 1 is a horizontal section at the level 75 of the stage floor through the theatre building, in which the present invention is fitted.

Fig. 2 is a perspective, yet schematic view of the arrangement as a whole.

The stage proper is formed of a platform 80 L disposed close to the prompter's box S, and behind the said platform L is a smaller platform l. Both these platforms are capable of moving vertically being arranged each one in its vertical elevator shaft, inside 85 which the platforms in known manner may move up and down. The elevator shaft of the large platform L extends as well as downwards through the cellar B below the stage room A upwards through the said 90 stage room and the stories situated above the same, while the elevator shaft for the small platform l only extends downwards through the cellar B. Both platforms are normally 95 at a level with the floor g of the stage A, and they are separated from one another by means of the upper surface of a partition wall W, said surface being level with the floor g, and the said partition wall extending 100 downwards through the cellar B and forming a separation between the two elevator shafts.

In the cellar B is located, at each side of the elevator shaft corresponding to the large platform, a chamber or room, a or b, 105 respectively, Fig. 2, while around the elevator shaft corresponding to the small platform is arranged a group of five chambers or rooms 1, 2, 3, 4 and 5. The cellar may be divided into two low stories each one having 110 chambers or rooms as those mentioned above.

In the form of construction as shown, the elevator shaft of the large platform L extends upwards through the stage room and further through a space, which is divided 5 into a first story C and a second story D, and if desirable a further third story may be provided through the floor E of which the elevator shaft is extending. In each of the stories C and D is arranged around the 10 elevator shaft a group of five chambers I¹, II¹, III¹, IV¹ and V¹ around the shaft in the story C, and I², II², III², IV² and V² around the shaft in the story D.

All the chambers in the cellar and in the 15 stories C and D are open towards the respective elevator shaft and in these chambers the scenes, which are to be used on the platforms L or l, respectively, are built up on special platforms on castors or wheels, 20 so that, when the respective stage platform has been raised or dropped to the level of the respective room, and the last used scene has been removed into an empty room, the freshly built up scene may be wheeled on 25 to the platform and thereon be again be dropped or raised to the level of the stage floor.

When the scene has thus reached the level 30 of the stage floor g it may either be left on its platform, or may also, if desirable, be wheeled forward towards the proscenium or in any other desired direction. The scene on the large platform may also be supplemented by one or several smaller scenes 35 from the smaller platform so that various combinations of scenes are possible, without each scene requiring more than a few minutes for being placed into position on the stage floor.

40 It is obvious that the arrangement hereinbefore described according to the present invention allows of producing a considerably larger number of scenes than the heretofore known systems, and at the same time, 45 of utilizing the full depth of the stage. Furthermore, the arrangement of building-

up rooms in the cellar beneath the stage floor affords a considerable saving as regards the erection of the theatre house itself.

50

I claim:

1. A theatre stage comprising a main elevator shaft extending above and below the stage, a platform movable in the shaft, a room on each side the shaft opening into the latter below the stage, and a group of 55 rooms above the stage arranged on each side of and behind the shaft communicating with each other and with the shaft.

55

2. A theatre stage, comprising a main elevator shaft extending above and below the stage, a platform movable in the shaft, a room on each side the shaft opening into the latter below the stage, a group of rooms 60 above the stage arranged on each side of and behind the shaft communicating with each other and with the shaft, an auxiliary shaft behind the main shaft extending below the stage, a platform movable in the auxiliary shaft, and a group of rooms 65 arranged on each side of and behind the auxiliary shaft communicating with the latter and with each other.

65

3. A theatre stage, comprising a main elevator shaft extending above and below the stage, a platform movable in the shaft, a room on each side the shaft opening into the latter below the stage, a group of rooms 70 above the stage arranged on each side of and behind the shaft communicating with each other and with the shaft, an auxiliary shaft behind the main shaft extending below the stage, a platform movable in the auxiliary shaft, and a group of rooms 75 arranged on each side of and behind the auxiliary shaft communicating with the latter and with each other, and a partition below the stage 80 between the main and auxiliary shafts.

75

In testimony that I claim the foregoing as my invention, I have signed my name.

DRAGUTIN ZABARATZ.
